EXPANSIBLE WORK-ENGAGING TOOL

Application filed October 12, 1927. Serial No. 225,646.

This invention relates to a tool for engaging work while being manipulated in a hole, and may be specifically embodied in a grab, casing spear or like tool having members 5 expandible and contractible to engage work such as casing, "fish" and the like.

It is necessary to obtain a firm hold upon such work, and tools of this character are manipulated from the surface of the ground. 10 The amount of movement permitted of the parts is limited. It is the primary object of this invention to provide a tool wherein a motion transmission is employed for expansion and collapsing of the work engaging 15 members which transmission will multiply the force transmitted to the work engaging members. A more specific object of this invention is to employ a jack screw mechanism and wedges or inclined planes for operating 20 the work engaging members, all arranged compactly in a strong and durable structure and easily manipulated.

Other objects and advantages will be made 25 fully apparent from the following specification considered in connection with the accompanying drawing, in which:

Fig. 1 is an axial section through a grab, the expander being shown in elevation; Fig. 2 is a section as seen on the line 2—2 of Fig. 30 1; Fig. 3 is an axial section of a fragment showing a different type of jack screw structure adaptable for the tools; Fig. 4 is a section as seen on the line 4—4 of Fig. 1; Fig. 5 is an axial section through a casing 35 spear, the expander being shown in elevation; Fig. 6 is a section as seen on the line 6—6 of Fig. 5; and Fig. 7 is an end elevation of a fragment of the grab jaws and body as seen on the line 7—7 of Fig. 5.

Referring with more particularity to Figs. 1, 2 and 4, the body of the grab is indicated by 10. It has a bifurcated lower end comprising opposing legs 11 and 12. These legs are alike in construction. The upper end of the body includes a socket 13, the bore thereof being internally threaded. On the legs and opposing each other are guide ribs 14 and 15 for the expander. The legs at their lower ends are bored to receive a pivot pin. 50 Slidably mounted in a bore at the bottom

of the socket in the body is an expander comprising a stem 15 reduced in diameter at the upper end as indicated by 16 and threaded at the uppermost end. The lower end of the expander includes a wedge 17. On the inclined faces of the wedge and projecting therefrom are dove-tail tenons 18 and 19. The side faces of the wedge head have slots in which the ribs 14 and 15 slide. Thus the expander head is maintained against side 55 movement as it is moved up and down in the body.

The work engaging members of the grab comprise jaws 20 and 21. The jaw 20 has a center eye 22 disposed between eyes 23 forming a part of jaw 20. A pivot pin 24 extends through the jaws and the legs of the body. The jaws have mortise grooves 25 and 26 for engagement by the tenons 18 and 19. 60

Obviously, the actual movement of the expander or wedge will cause the jaws to be expanded and contracted. By projecting the wedge head between the jaws, their grabbing ends are brought together so as to collapse or contract the latter. A great deal of force is required to obtain a firm hold, and, to this end, I have provided a jack screw mechanism to project and retract the expander. A screw member 27 is rotatably mounted upon the reduced portion 15 of the stem and held in position by a nut 28. The screw member has an external square thread which meshes with the internal thread in the socket 13 of the body. The upper end of the screw is provided with a box 29 having a tapered threaded socket to receive the pin end of a tool joint 30 or like member. It will be noted that the external shoulder below head 29 will abut the upper edge of socket 35 13 so as to prevent binding of the threads and permit backing off with ease. The tool joint is provided with a bore for circulation and as will be noted from an inspection of Fig. 2, and the expander is likewise provided with a circulation passage extending through the center.

To operate the tool just described, it is lowered in the hole with the jaws expanded until the "fish" is engaged, the tool being landed. Thereupon, the drill stem is rotated causing 95 100

rotation of the screw 27. Rotation is effected in the direction such as to advance the screw into the socket so as to project the wedge between the jaws and thereby to contract the latter. Obviously, to expand the jaws, the direction of rotation is reversed. However, when a "fish" has once been engaged, a firm hold is obtained thereon and the "fish" is elevated.

In Fig. 3, a modified form of jack screw structure is shown. There is a body 10^a having legs 11^a and 12^a and a socket 13^a. The socket has a smooth bore except for the upper end which is threaded as indicated by 31. The stem 15^a is externally threaded and engages a rotatable sleeve 32 having a thread therein at the lower end. The upper end has a box 33 with a tapered threaded socket for the reception of a pin end of a tool joint. A shell 34 is engaged with the thread 31 and extends into the socket of the body engaging a shoulder at the lower end of the sleeve. The upper end engages an opposing shoulder on the sleeve. This swivels the sleeve to the body and permits free rotation which may be effected by the drill string. It is apparent that rotation of the drill string will cause the threaded stem 15^a to be raised and lowered so as to effect expansion and collapse of the jaws.

Referring more particularly to Figs. 5, 6 and 7, the invention is shown embodied in a grab. The grab comprises a body 35, bifurcated at the lower end to provide legs 36 and 37. Pivottally mounted in the legs is a set of jaws 38 and 39 of the same general construction so far as mounting is concerned as the grab jaws. However, the jaws are intended to expand and engage a casing or the like, and the upper ends of the jaws are for this purpose. The jaws are corrugated or serrated as indicated by 40. As the tool is not landed on the bottom and has to have means on the side to engage the casing and to hold the body against rotation, I have provided springs 42 and 43 intended to frictionally engage the inside of the casing. The jaws at their inner and upper opposing faces are provided with mortise groove for the engagement by tenons on the expander head 44. The expander head is substantially identical with that before described, the stem 45 thereof extending into the socket on the body. The stem extends slidably and rotatably through the screw 46 having a thread meshing with the thread in the box of the body 35. There is a threaded pin 47 at the top of the screw member engaged in the box of a tubular member 48. The bore in the screw member 46 is threaded at the upper end to receive an adjustment sleeve 49. The adjustment sleeve abuts at its lower face a shoulder on the stem 45. The upper reduced end of the stem is threaded as indicated and receives a nut 51. Obviously,

the nut 51 and sleeve 49 serve to provide a swivel connection between the stem 45 and the body of the tool together with the string of drill pipe. By turning the drill string and screw 46 therewith, the stem will be compelled to move axially within the body 35, so as to expand and collapse the jaws. The initial expansion of the jaws is obtained by adjusting the sleeve 49 up or down with the screw. The tool is operated by lowering it in the casing until the point is reached in which a hold is desired. The leaves 42 and 43 will frictionally engage the casing and resist turning of the lower end of the tool, so that upon turning the drill string, the screw 46 will be moved up or down and thereby the wedge 44 will be projected between the jaws or retracted depending upon the direction of rotation.

Various changes may be made in the structure to provide a jack screw connection between the expander and the drill string. There are various other mechanical variations possible making the tool adaptable for other purposes.

What I claim is:

1. A tool of the character described comprising a body, work engaging jaws pivotally secured together intermediate their ends and mounted on said body, an expander having a stem and a wedge head converging toward the front and disposed to engage said jaws at the rear of the pivotal axis to cause collapse and expansion of said jaws, a screw member rotatably mounted on said stem and adapted to be connected to a drill string, said body having a threaded socket in which said screw member is engaged whereby rotation of the drill string will cause projection and retraction of said expander.

2. A tool of the character described comprising a body, work engaging jaws pivotally secured together intermediate their ends and projecting in advance of said body, an expander having a stem and a wedge head converging toward the front and positively engaged with said jaws at the rear of their pivotal axis a screw member rotatably mounted on said stem and adapted to be connected to a drill string, said body having a threaded socket in which said screw member is engaged whereby rotation of the drill string will cause projection and retraction of said expander.

3. A tool of the character described comprising a body, work engaging jaws pivotally secured together intermediate their ends and mounted on said body to project therefrom an expander having a stem and a wedge head for projection and retraction between said jaws and engaged therewith at the rear of the pivotal axis, said wedge head converging toward the front, jack screw means rotatably mounted on said stem

so as to compel axial movement of the latter and coupled to said body whereby rotation of one of said jack screw members in one direction will advance said stem and cause collapse of the front ends of said jaws and rotation in the opposite direction will cause expansion thereof.

In witness that I claim the foregoing I have hereunto subscribed my name this 29th

10 day of September, 1927.

ERNEST KOPPL.
